UNITED STATES PATENT OFFICE.

MICHAEL BETKE, OF DENVER, COLORADO.

AUTOMATIC RAIL-JOINT FASTENING.

Application filed January 12, 1925. Serial No. 2,022.

To all whom it may concern:

Be it known that I, MICHAEL BETKE, a citizen of the United States of America, and a resident of the city and county of Denver, State of Colorado, have invented certain Improvements in Automatic Rail-Joint Fastenings, of which the following is a specification.

An object of this invention is to provide improved means for tightening the nuts of rail joint fastenings by means of devices operated by wheels passing over said rail joints.

The invention consists in the construction, arrangement and combination of elements hereinafter set forth, pointed out in my claims and illustrated by the accompanying drawing in which—

Figure 1 is a plan of abutting end portions of railway rails to which my improvements are applied. Figure 2 is a side elevation of the same, truck wheels being shown surmounting the rail. Figure 3 is a cross section on the indicated line III—III of Figure 2. Figure 4 is a detail face view of one of the operating elements detached from the remainder. Figure 5 is a side elevation of a detent employed in the device. Figure 6 is a side elevation of a spring employed in the device.

In the construction of the devices as shown, the numeral 1 designates either portion of abutting railway rails, forming a joint, and the numerals 2 and 3 designate fishplates mounted in the usual manner on said rail portions and overlapping the joint between them. The fishplate 3 has its upright portion of materially greater thickness than that of the fishplate 2, in order to fill the space at one side of the rails and bring the outer face of said fishplate 3 into a vertical plane outside of that of one side of the tread of said rails. The fishplates 2 and 3 and the webs of the rail portions are formed with the usual bolt-holes, and fastening bolts 7, in this instance four in number, being mounted thru said holes. Nuts 8, each formed with a ratchet wheel base portion 8' are mounted on the threaded end portions of the bolts 7 and are adapted to be employed to clamp the fishplates to the rail portions. The fishplate 3 also is formed with upright lugs 9, spaced apart to form slide bearings between them, opposed faces of said slide bearings being parallel. Some of the lugs 9 are of single

form and of different widths and some of said lugs are of double form, as clearly illustrated in Figure 2. Plates 4, in this instance four in number, are slidably mounted in the slide bearings provided by the lugs 9 and are contained between the ratchet wheel portions 8' of the nuts and the outer face of the fishplate 3. The upper portions 10 of the plates 4 are of greater thickness 60 than the bodies thereof and are adapted to project outwardly over the vertical plane of the ratchet wheel portions 8'. The bodies of the plates 4 also are formed with upright slots 11 (Fig. 4) adapted to receive the bolts 7 and permit said plates to be reciprocated vertically relative to said bolts and in the slide bearings. Detents 5 of elbow shape, are pivoted by rivets 12 located at their angles, to the body portions of plates 4, one 70 arm of each detent extending horizontally beneath and in contact with a shoulder formed by the lower margin of the head portions 10 of said plates. The other arm of each detent 5 is formed with teeth 13, in 75 this instance two in number, slightly spaced apart and on the inner face of said arm and said arm extends vertically across the plate and intersects the orbit of a ratchet wheel portion 8'. A spring 6, of hair pin type, is 80 formed with a nearly-closed eye in its central portion adapted to be engaged by a pin 6' cleated in the fishplate 3 adjacent to one of the lugs 9. One arm of the spring 6 is curved upwardly and engages at its extremity with 85 the lower face of the horizontal portion of the detent 5 while the other arm of said spring is bent downwardly and is adapted to engage one or another of the teeth of the ratchet wheel portion 8' and prevent reverse 90 rotation thereof.

In practical use the several nuts 8 are tightened on the bolts 7 with the plates 4 in their lower-most positions, as shown at the left half of Figure 2. Thereafter, in 100 use, one or more of the nuts 8 may become loosened so as to destroy the clamping effect of the bolt 7 on which it is mounted and, in that event, the plate 4 adjacent thereto will be relieved from the clamp 105 and rise, because of expansion of a spring 6, into the position shown in the right half of Figure 2. When a railway motive element, such as a locomotive or car, next passes over the joint containing such loosened nut, one or more wheels 14 thereof will 110 engage with and depress the upstanding

plate, the upper margins of the heads of the plates being made convex to accommodate such impact. The depression of a plate 4 carries the detent 5 thereon downwardly and causes the teeth 13 to engage successively with the teeth of the ratchet wheel portion 8' and rotate the nut 8 thereon in tightening direction. When the nut 8 is again tightened to the desired extent by successive impacts of successive wheels 14, it will hold the plate 4 in its lowermost position. Thus, provision is made for automatically tightening any nut which becomes loose in use on a joint of this character.

I claim as my invention—

1. In an automatic rail joint fastening, the combination of ratcheted nut members, spaced operating plates severally located adjacent thereto and adapted to project at times above normal positions; and means carried by the several operating plates adapted to engage and rotate said nut members.

2. In a device of the character described having abutting railway rails, fishplates overlapping the joint thereof, and bolts extending thru said rails and fishplates, the combination of operating plates mounted for reciprocation on said fishplates, nuts mounted on said bolts, and detents carried by said plates and adapted to engage said nuts.

3. In a device of the character described the combination of abutting rail sections, fishplates overlapping the joints thereof, one of said fishplates having its outer face in a plane outside of the outer face of the tread of the rail and also formed with slide

bearing bolts connecting said rails and fishplates, plates formed with slots adapted to receive said bolts and mounted for reciprocation in said slide bearings, ratcheted nuts on said bolts and detent devices on said plates adapted to engage said nuts.

4. In a device of the character described, the combination of abutting rail sections, fishplates overlapping the joints thereof, one of said fishplates having its outer face in a plane outside of the outer face of the tread of the rail and also formed with slide bearing bolts connecting said rails and fishplates, plates formed with slots adapted to receive said bolts and mounted for reciprocation in said slide bearings, ratcheted nuts on said bolts, detent devices pivoted on said plates adapted to engage said nuts, and springs carried by said fishplate and engaging said nuts and detent devices.

5. In a device of the character described, a fishplate formed with slide bearings arranged transversely and in spaced relation, said fishplate being formed with holes between said bearings adapted to receive bolts, plates mounted for reciprocation in said bearings and formed with slots adapted to receive said bolts, ratcheted nuts between said bearings, detent devices on said plates adapted to engage said nuts and hair pin springs on the fishplate adapted to engage the nuts and detent devices.

6. In a device of the character described a plate having a laterally extended head adapted for impact and a detent device pivoted on said plate beneath and adapted to engage said head.

MICHAEL BETKE.
